HAND KNITTING OR CROCHETING DEVICE

Anne Coffey, New York, N. Y., assignor to Coffey Creations, Inc., New York, N. Y., a corporation of New York

Application February 23, 1946, Serial No. 649,607

3 Claims. Cl. 66—125)

1

This invention relates to hand knitting and crocheting devices.

The average person, in knitting garments, stockings, and other articles, holds a knitting needle in each hand and draws the yarn from one hand to the other, the yarn from a ball of yarn being usually wrapped in one or more turns on, say, a finger of the hand to maintain a desired tension on the yarn as it is picked up by the needle to which it is directed. However, difficulty is frequently experienced in maintaining the desired tension on the yarn and unevenness in the stitch results.

One object of this invention is an instrumentality which will enable a constant tension to be maintained on the yarn.

Another object of the invention is a yarn tensioning device which may be carried on the hand without inconvenience while knitting.

It is also an object of the invention to eliminate the wrapping or turning of a length of the yarn about the fingers.

A further object of the invention is to automatically control the transit of yarn or thread from the hand of the knitter or crocheter to the contact point of the stitch on the needle or needles.

More particularly, the invention seeks to control the tension of the yarn adjacent to the point of stitch on the needles, so that the stitching is evenly placed and knitted or crocheted.

It is still another object of the invention to provide an exact control of the stitch, as distinguished from the otherwise variable control by the fingers which results in loose, tight or uneven knitting or crocheting depending on the skill of the operator, knitter or crocheter.

A further object of the invention is a device in which any kind of thread or yarn, or strand of plastic material may be used.

Still another object of the invention is a hand knitting device which will control the tension of strands from the finest to the thickest strand whether of yarn, thread or of plastic strands.

These and other objects of the invention and the means for their attainment will be more apparent from the following detailed description, taken in connection with the accompanying drawings, illustrating one embodiment by which the invention may be realized, and in which:

Fig. 1 is an exploded view showing the component elements of the invention;

Fig. 2 is a view in perspective showing the yarn tensioning device of this invention in elevation;

2

Fig. 3 is a view showing how the invention is used in the hand in knitting; and

Fig. 4 is a perspective view of the position of the device of this invention in use.

5 Referring first to Fig. 1, the components of the hand knitting or crocheting device comprises a support, for instance a spindle 5 formed with a transverse slot 10 in its upper end and whereof the forked ends 11 are shown formed with threads 14 intermediate the upper ends 16 and the bottom 18 of the slot 10. Intermediate the bottom 18 of the slot 10 and the lower threaded stud 20 of the spindle 5, the spindle is provided with a cylindrical portion 22 of greater diameter which 15 provides an upwardly facing shoulder 24 and the lower end of the spindle is again reduced in diameter as at 20 and the reduced portion 20 is formed with threads 28.

Resting on the shoulder 24 is an inverted 20 saucer-like yarn guide 4 which supports an upwardly facing yarn guide member 3 (see also Fig. 2). The abutting surfaces of these two members, 3 and 4, define a rotatable yieldable clamp 30 through which the yarn passes and by which the 25 yarn is tensioned. The dished annular yarn guides, 3 and 4, have openings 34 that fit down over the forked end 11 of spindle 5 and permit yarn guide 4 to rest on shoulder 24. A coil spring 2, or other expandable means, rests upon the upper face of yarn guide 3, the bottom of the coil resting in the annular depression 33 of the upper yarn guide 3. When assembled, the lower yarn guide 4 rests on the shoulder 24 and, in addition, on its upper face, supports the yarn guide 3.

35 Adjustable compression of the spring 2 by the nut 1 maintains the yarn guides 3 and 4 yieldingly in contact with one another whereby a thread or yarn may be yieldingly held between the yarn guides, as shown in Fig. 2. Obviously, 40 other suitable yarn tensioning devices yieldingly passing the yarn are equally within the purview of this invention.

A structure, which may be similar to one of the 45 yarn guides 3 or 4 may serve as a palm engaging member 6 which is placed over the threaded stud 20 and is held in position against the bottom of the cylindrical portion 22, as by the nut 7 or other suitable retaining means.

When the parts are assembled, as in the Fig. 2 disclosure, and ready for use, the palm engaging member 6 is held against the palm of the one hand with the spindle 5 passing outwardly between two fingers, say, the first and second fingers of the one hand, and so that the two yarn guides 3 and 4 are outwardly of the back of the

hand where they are pressed toward one another by the spring 2. Tension of the spring to place the desired tension on the thread or yarn is effected by screwing down the nut 1 to compress the spring, as desired, against the upper yarn guide 3, although other means of accomplishing control of the tension may be availed of. The yarn is yieldingly gripped between the yarn guides 3 and 4 and the yarn can be readily drawn through the yarn guides, the yarn guides effecting the desired tension on the yarn as it is drawn through in knitting or crocheting.

It will be understood that the hand knitting or crocheting device of this invention is most conveniently held in the hand with the shaft portion 22 between the index finger and the second finger of either hand, as shown in Fig. 3, and maintains its place by spring pressure without any conscious effort on the part of the knitter or crocheter. Furthermore, the same spring 2 controls the pressure of the yarn or thread in transit to the needle.

The end of the yarn or thread from a ball of yarn or thread is placed through and between the two yarn guides and the tension required for each transit between or through the yarn guides is adjusted by turning pressure nut 1 to compress the spring. This sets the required tension for knitting or crocheting the kind of thread or yarn being used. Knitting or crocheting proceeds after placing portion 22 of the device between the index finger and the second finger of either hand, as shown in Fig. 3, and then attaching the yarn to the needles 9 and 9B and proceeding as in the accepted manner of knitting or crocheting, as shown in Fig. 3.

What is claimed is:

1. A hand knitting and crocheting device comprising a shaft formed with an axial slot, a portion of the shaft formed with the slot being

threaded, yarn guides comprising, respectively, plane central surfaces and dish-shaped yarn guiding surfaces, a spring to urge the yarn guides into contact with one another, and a nut-like member to control the tension of the spring.

2. A hand knitting and crocheting device comprising a shaft, yarn guides comprising, respectively, plane central surfaces and annular yarn guiding surfaces, a spring to urge the yarn guides into contact with one another, a nut-like member to control the tension of the spring, a threaded pin on the opposite end of the shaft, a dish-shaped disc on the threaded pin, and a nut to retain the disc on the shaft.

3. A hand knitting and crocheting device comprising a shaft, yarn guides comprising, respectively, plane central surfaces and annular yarn guiding surfaces, a spring to urge the yarn guides into contact with one another, a nut-like member to control the tension of the spring, a threaded pin on the opposite end of the shaft, a dish-shaped disc on the threaded pin, and a nut to retain the disc on the shaft comprising finger gripping means.

25 ANNE COFFEY.
